Primary Examiner — Vy Koenig*Assistant Examiner* — Kimberly Barnes(74) *Attorney, Agent, or Firm* — Leanne Taveggia Farrell; Westman, Champlin & Koehler, P.A.(57) **CLAIM**

The ornamental design for a structured queuing assembly, as shown and described.

DESCRIPTION

FIG. 1 is a front perspective view of a structured queuing assembly showing our new design;

FIG. 2 is a back perspective view thereof;

FIG. 3 is a partial enlarged view of FIG. 2;

FIG. 4 is a front elevation view thereof;

FIG. 5 is a back elevation view thereof;

FIG. 6 is a left side elevation view thereof;

FIG. 7 is a right side elevation view thereof; and,

FIG. 8 is a top elevation view thereof.

The broken lines shown in the drawings are included for purposes of illustrating portions of the structured queuing assembly that form no part of the claimed design.

1 Claim, 6 Drawing Sheets(56)
